[57] CLAIM

The ornamental design for a vehicle disc brake shoe, substantially as shown and described.

DESCRIPTION

FIG. 1 is a front perspective view of a vehicle disc brake shoe embodying our new design.

FIG. 2 is an inverted rear perspective view thereof.

FIG. 3 is an enlarged cross-sectional view thereof taken along line 3—3 in FIG. 1.

FIG. 4 is a front perspective view of a vehicle disc brake shoe showing a second embodiment of our new design, the differences being in the vertical groove cut into the front planar surface and the beveled end portion.
